No. 802,697.

PATENTED OCT. 24, 1905.

H. T. JOHNSON.
CIRCUIT CONTROLLING DEVICE.
APPLICATION FILED APR. 2, 1904.

UNITED STATES PATENT OFFICE.

HARRY T. JOHNSON, OF JERSEY CITY, NEW JERSEY.

CIRCUIT-CONTROLLING DEVICE.

No. 802,697.

Specification of Letters Patent.

Patented Oct. 24, 1905.

Application filed April 2, 1904. Serial No. 201,302.

To all whom it may concern:

Be it known that I, HARRY T. JOHNSON, a citizen of the United States, and a resident of the city of Jersey City, Hudson county, New Jersey, have invented certain new and useful Improvements in Circuit-Controlling Devices, of which the following is a full, clear, and exact description, reference being had to the accompanying drawings, forming a part of this specification.

My invention relates to apparatus for opening and closing an electric circuit, and is especially adapted for employment in a circuit which includes an indicator designed to give an alarm when some object by which the indicator is held inoperative is surreptitiously or improperly moved or actuated. As more specifically describing one field of usefulness for my invention, a burglar-alarm system may be referred to in which an audible or visual alarm is arranged to be given by the movement of some object—such, for instance, as a chair so placed in front of the entrance to a room that it would naturally or inevitably be moved from such position by any person surreptitiously entering the room; and in order that my invention and its mode of operation may be fully but succinctly described I have illustrated and will hereinafter describe the same as it is used in such a burglar-alarm system.

In the drawings, Figure 1 is a central longitudinal section with the contacts held apart by the weight of a chair. Fig. 2 is a plan view. Fig. 3 is a central longitudinal section showing the contacts closed and also showing a modification. Fig. 4 is a central longitudinal section showing the parts locked in inoperative position with the contacts apart and the circuit open, and Fig. 5 is a plan view thereof.

Similar reference characters are employed to designate like parts in all the views.

The particular form of apparatus embodying my invention which I have illustrated is preferred by me for the particular use to which I have before referred. It consists of a cylindrical shell 1, of conducting metal, provided with a flange 2. A lug 3 is formed on one side of the shell and is apertured to receive the screw 4, which serves both as a binding-screw for one wire 6 of the circuit and also to hold the device firmly in an aperture formed to receive it in the floor 7. The opposite (or when in the position shown the lower) end of the shell 1 is formed with an inturned flange 9, upon which rests the insulating and center-

ing washer 10, which supports the flanged conducting-bushing 11 and centers it in position out of contact with the shell 1. The bushing is exteriorly screw-threaded to receive the screw-threaded binding-washers 14 and 15, between which is clamped the other wire 16 of the circuit. An insulating-washer 17 is clamped between the washer 15 and the end of the bushing 9. A plunger 20 is fitted to reciprocate in the shell 1 and in contact therewith and is provided with a contact-stem 21, both the plunger and contact-stem being formed of conducting metal. An insulating-washer 22 rests upon the top of the bushing 11 and supports a washer 23, which serves as an abutment for the open-coil helical spring 24, which encircles the stem 21 and bears against the under surface of the plunger. The lower end of the stem 21 is split, and the two sections 26 of the ends thus formed are spread apart after the plunger is inserted in the shell, so that they will contact with the lower end of the bushing to close the circuit and also to confine the plunger 20 in the shell.

In order to prevent the normal operation of the device, I provide a suitable locking means by which the parts of the device may be held fixedly in position to prevent the alarm or indicator from operating when desired. This, as will be understood by those skilled in the art, may be accomplished in many ways, and in the drawings I have shown one simple and effective means for accomplishing this, which I will now proceed to describe, but to which it is to be understood my invention is not restricted further than the limitations in the phraseology of the claims may expressly require. The means illustrated comprise a pin or lug 28 on the inner wall of the shell 1. The plunger 20 is provided with a longitudinal groove 29, into which the pin 28 projects, the pin thus furnishing no obstacle to the reciprocation of the plunger. The groove 29 at its upper end communicates with the horizontal or transverse slot 30, which at its center is deeper than the length of the pin 28, so that when the plunger is depressed, so that its top is substantially flush with the top of the shell, it may be rotated on its axis to cause the pin 28 to enter the transverse slot. When so turned, the pin will hold the plunger and prevent its upward movement and the contacts 26 will be held away from the lower end of the bushing 11, as shown in Fig. 4. To permit the convenient rotation of the plunger, I provide the top thereof with a slot or depression 31,

as shown in Fig. 3, in which a suitable implement, such as a screw-driver, may be inserted, or the top of the plunger may be roughened by providing it with a number of depressions, so that the plunger may be rotated without the aid of such implement.

When used on an open circuit, the operation of the form of device illustrated is as follows: The device having been properly secured in position—as, for instance, in front of a door or entrance to a room—and the circuit-wires having been properly connected to the terminals, as shown, the plunger is depressed, and one of the legs of a chair 32 or 15 any other suitable movable object of sufficient weight is placed over the device, so that the chair-leg or other object will hold the plunger down against the pressure of the spring 24, the object being so placed that it will conceal the device and will naturally be moved 20 by any person on entering the room. When so moved, the plunger being released will be pressed upwardly by the spring 24. The contacts 26 will engage the bottom of the bushing 11, closing the circuit at that point and 25 operating a signal or alarm suitably located at any distant point.

To render the device inoperative—as, for instance, during the day-time or when the 30 room is legitimately occupied—the plunger is depressed and rotated slightly. The pin 28 will enter the slot 30, and the circuit will thus be held open until it is desired to restore the device to operative condition when the 35 plunger is turned in the reverse direction until the pin again enters the groove 29, releasing the plunger.

Having thus shown and described my invention, what I claim as new, and desire to secure 40 by Letters Patent, is—

1. In a circuit-controlling device, the combination of a conducting-shell carrying a fixed contact insulated therefrom, means for connecting said contact with one wire of the circuit, a spring, a movable contact held against 45

said fixed contact by the spring and working in contact with the shell, means for connecting the shell with the other wire of the circuit, a pressure-controlled plunger for separating said contacts, and locking means for 50 the plunger for holding the contacts apart and rendering the device inoperative when the plunger is relieved from pressure.

2. In a circuit-controlling device, a shell, a pressure-controlled plunger working therein, 55 a spring for actuating said plunger to close the circuit when the plunger is relieved from pressure, and means for rendering the device inoperative by the rotation of the plunger.

3. In a circuit-controlling device, the combination of a shell, a plunger working in the shell adapted to be held within the shell by pressure exerted on the end thereof, a spring for elevating the end of said plunger above 65 the shell when the pressure is removed, contacts adapted to be closed when the plunger is elevated and means for locking the plunger in the shell against the action of the spring to render the device inoperative when such pressure is removed. 70

4. In a circuit-controlling device, the combination of a shell and a spring-pressed reciprocating plunger therein, a lug on one of said parts, a longitudinal groove and a transverse slot communicating therewith in the other part to permit the reciprocation of said plunger by pressure exerted thereon, and to permit the locking of the plunger by a rotational movement thereof. 75

5. In a circuit-controlling device comprising a shell and a spring-actuated plunger working therein to open and close the circuit, means for locking the plunger in the shell by rotating the plunger and a depression or depressions formed in the top of the plunger, 80 for the purposes set forth. 85

HARRY T. JOHNSON.
